UNITED STATES PATENT OFFICE.

HUGH BROOKS SHUTTS, OF SHAWNEETOWN, ILLINOIS, ASSIGNOR OF TWO-THIRDS TO DENT REID AND WINFIELD S. PHILLIPS, OF RIDGWAY, ILLINOIS.

DUST-GUARD FOR CAR-WINDOWS.

SPECIFICATION forming part of Letters Patent No. 634,770, dated October 10, 1899.

Application filed December 31, 1898. Serial No. 700,806. (No model.)

To all whom it may concern:

Be it known that I, HUGH BROOKS SHUTTS, of Shawneetown, in the county of Gallatin and State of Illinois, have invented a new and Improved Dust-Guard for Car-Windows, of which the following is a full, clear, and exact description.

My invention relates to an improvement in those devices which are attached to the sides of car-windows and intended for keeping dust and cinders from entering the window while open and while the cars are in motion.

My invention consists of the novel features hereinafter described and claimed.

Reference is to be had to the accompanying drawings, forming a part of this specification, in which similar characters of reference indicate corresponding parts in all the figures.

Figure 1 is a side-elevation of part of a car with my device attached to one of the windows. Fig. 2 is a sectional elevation on the line 2 2 in Fig. 1. Fig. 3 is a sectional plan on the line 3 3 in Fig. 1, and Fig. 4 is a perspective view showing my device detached and also showing it as provided with an auxiliary wing.

Dust-guards for car-windows are usually made detachable and are not in position except when put in use. My device is intended to be attached to the car-window at all times, so that a passenger may put it into use whenever desired. It is also provided in duplicate, one being placed on each side of the window, and is thus in position for use in whichever direction the car is traveling.

A plate D, of thin metal, is secured to the face of the window-casing B at one side thereof and immediately outside of the stile b for the sash C. To this plate D is hinged a second plate E, this latter plate forming the dust-guard, said plate E extending from the window-sill A upward to a height corresponding with the maximum elevation of the car-window. Upon the plate D is pivoted a lever F, the pivot f of which is located close to the inner edge of the plate, so that the lever F when placed in a vertical position will have its inner edge in contact with or close to the outer surface of the window-sash. This lever F, as herein shown, is of angular cross-section, one of the flanges bearing against

the surface of the sash when said sash is down. This position of the device is shown by dotted lines in Fig. 2.

At the outer end of the lever F is pivoted a link G, which is secured to the hinged plate E by means of a staple g. When the lever F is thrown to the horizontal position shown by full lines in Fig. 2, it forces the hinged plate E outward at an angle with the side of the car, which angle, as herein shown, is substantially forty-five degrees, but which may be varied as desired in any particular case. The width of the plate E should be such as is found necessary to make an efficient dust-guard, the width depending upon the width of the window, a broad window requiring a broad dust-guard. The width of the plate is, however, limited to the depth of the window-casing. In cases where the depth of the casing is not sufficient to permit a plate of proper width to fold down outside of the sash the plate E is augmented by a second or auxiliary plate E', hinged to the outer edge. Such a plate is shown in Fig. 4, and its hinge swings in the opposite direction from that of the hinge between the plates D and E.

To the lower end of the plate E is hinged an auxiliary plate H, which is notched at its lower edge, so that it will fully close the space between the lower end of the plate E and the window-sill. This construction is rendered necessary by reason of the bevel of the window-sill, as otherwise there would be a gap between the plate and the sill, through which dust would be likely to enter.

When the device is in use, the lever F extends inward at the side of the window, where it will be engaged by the sash when lowered. The operation of the device is therefore in a measure automatic, the device being folded inward by the engagement of the sash with the lever F when the sash is lowered.

It will ordinarily be found sufficient to have one of these devices in operation. When it is found necessary, however, the second may be brought into use in the manner shown in Fig. 3. As the device is shown in Fig. 3 the guards are adjusted for use when the car is moving toward the right. The forward guard is shown fully extended, while the rearward guard is only partially extended. In this po-

sition it will prevent some cinders from entering the window, which otherwise would strike the window-casing and rebound into the car. Such cinders when my device is in use 5 strike the sloping surface of the rear guard and rebound outside of the car instead of passing to the inside. It is, in fact, not really necessary to shift the rear guard, as it will accomplish this purpose when folded inward. 10 This device being always in position may be operated by the passenger and adjusted to suit his own convenience.

The lever F, projecting within the car when the device is thrown outward, will make it 15 impossible to leave the device extended when the window is closed.

Having thus fully described my invention, I claim as new and desire to secure by Letters Patent—

20 1. The combination with the window frame and sash, of a dust-guard mounted at one side thereof to swing inward and outward, a lever fulcrumed at one side of the frame and adjacent to the dust-guard, and a link connecting

the lever with the dust-guard, the lever being juxtaposed to the sash so that the movement of the same actuates the lever. 25

2. The combination with a window frame and sash, of a plate secured rigidly thereto at one side thereof, a dust-guard hinged to 30 the plate to swing inward and outward, a lever fulcrumed on the plate, and a link connecting the lever with the dust-guard, the lever being juxtaposed to the sash so that the movement of the same actuates the lever. 35

3. The combination of a dust-guard, adapted to be mounted to swing at one side of a window-frame, and an auxiliary or extension plate hinged to the lower edge of the dust-guard and adapted to engage the window-sill 40 when the dust-guard is moved inwardly and to extend downward below the sill when the dust-guard is moved outwardly.

HUGH BROOKS SHUTTS.
